(57) **CLAIM**

The ornamental design for a fishing lure blade attachment clip, as shown and described.

DESCRIPTION

FIG. 1 is a front perspective view of a fishing lure blade attachment clip showing my new design;

FIG. 2 is a rear perspective view thereof;

FIG. 3 is a front view thereof;

FIG. 4 is a rear view thereof;

FIG. 5 is a side elevational view thereof;

FIG. 6 is a top plan view thereof;

FIG. 7 is a bottom plan view thereof;

FIG. 8 is a first perspective view illustrating my inventive fishing lure blade attachment clip used in combination with a fishing lure and blade;

FIG. 9 is a second perspective view illustrating my inventive fishing lure blade attachment clip used in combination with a fishing lure and blade; and,

FIG. 10 is a third perspective view illustrating my inventive fishing lure blade attachment clip used in combination with a fishing lure and blade.

The phantom lines in FIGS. 8–10 depict environmental structure and are for illustrative purposes only to show a sample fishing lure blade and a sample fishing lure to which the blade is attached by my inventive fishing lure blade attachment clip.
